J. P. STREET

CABLEWAY CARRIAGE

Filed June 26, 1922

2 Sheets-Sheet 2

UNITED STATES PATENT OFFICE.

JOSEPH P. STREET, OF CHATTANOOGA, TENNESSEE, ASSIGNOR TO STREET BROS.
MACHINE WORKS, OF CHATTANOOGA, TENNESSEE.

CABLEWAY CARRIAGE.

Application filed June 26, 1922. Serial No. 570,811.

To all whom it may concern:

Be it known that I, JOSEPH P. STREET, a citizen of the United States, residing at Chattanooga, in the county of Hamilton 5 and State of Tennessee, have invented a new and useful Cableway Carriage, of which the following is a specification.

This invention relates to carriages for use in connection with aerial cableways such as 10 employ carriers for supporting the running lines of the cableways.

One of the objects of the invention is to provide a carriage which, when moved along a cableway, will deliver rope carriers at substantially regular intervals onto the supporting cable and will subsequently pick up the rope carriers successively and convey them back to the point of starting.

A further object is to provide the carriage with novel means for ejecting the rope carriers, said means including a differential mechanism by means of which ample space is provided for the reception of the first carrier subsequent to its ejection from the carriage and during the return or collecting trip of the carriage.

Another object is to provide simple and efficient means whereby that portion of the carriage engaging the carriers is substantially counterbalanced, thus to maintain that portion of the carriage which supports the carriers, commonly called the horn, properly positioned relative to the track rope or cable.

With the foregoing and other objects in view which will appear as the description proceeds, the invention resides in the combination and arrangement of parts and in the details of construction hereinafter described 35 and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a side elevation of the apparatus constituting the present invention.

Figure 2 is a plan view thereof, a portion being shown in section.

Figure 3 is a section on line 3—3, Figure 2.

Referring to the figures by characters of reference A designates the main or supporting cable of an aerial carriage and mounted to travel thereon are supporting sheaves 1 preferably arranged in pairs, the sheaves of each pair being journaled between side plates 2 which, in turn, are connected as by 55 means of bolts 3, to the upper corner portions of the side plates 4 of the carriage body. Small supplemental sheaves 5 are journaled on the bolts 3 and are supported close to and under the cable A so as to hold the 60 sheaves 1 on said cable. An in-haul line 6 is attached to one end of the carriage body while an out-haul line 7 is connected to the other end of the body. Interposed between the side plates 4 of the body are sheaves 8 65 adapted to support the cables of a hoist, not shown while arranged between the side plates 4 and above and adjacent one of the sheaves 8 is a small sheave 9 adapted to support that portion of the out-haul line 7 70 that extends back through the aerial carriage to the mechanism (not shown) utilized for operating the line.

One of the sheaves 1 is secured in any suitable manner to a rotatable shaft 10 journaled in suitable bearings 11 carried by the plates 2. To one end of this shaft 10 is secured a beveled gear 12 which constantly meshes with a larger beveled gear 13 secured to a longitudinal shaft 14 journaled within 80 a laterally extending bearing 15. This bearing is attached to one side portion of a forked arm 16 which straddles one pair of side plates 2 and is fulcrumed on the shaft 10.

Pivotedly connected to each of the side plates 4 of the body is a counterbalance lever 17 having a forked end 18 adapted to work along an arcuate guide 19 secured to the side plate 4. Mounted on each lever 17 is a 85 weight 20 which can be held in any desired position by means of set screws 21. Links 22 connect the levers 17 to the adjacent ends of the forked arm 16 and weight 20 is of such mass as to yieldingly maintain the horn 100 23 elevated with reference to the cable A.

The arm 16 is extended beyond one end

of the carriage body and has its side portions converging toward the free end of the arm where they emerge into a horn 23 the free end of which is inclined downwardly toward 5 the cable A and upwardly to a retaining shoulder 24.

Slidable on the arm 16 adjacent the side plates 2 is a cross head 25 having guides 26 in which is slidably mounted a push bar 27 having a link 28 pivotally connected thereto as shown at 29. This link is also pivotally connected to a crank pin 30 eccentrically mounted on and rotatable with a gear 31 suitably supported within the cross 15 head. Said gear meshes with a segmental gear or rack 32 formed at one end of a bell crank 33 fulcrumed at 34 on a suitable bracket 35 extending from the cross head. The other end of the bell crank has a pin 36 20 extending downwardly therefrom and this pin projects into engagement with a worm 37 carried by a sleeve 38 which is feathered on the shaft 14 so that the worm will rotate with the shaft while the shaft is capable 25 of sliding within the sleeve 38. The ends of the worm terminate short of the ends of the sleeve 38 so that the spiral groove formed between the thread of the worm opens at its ends within annular 30 grooves 39 at the end portions of the sleeve 38. This will be apparent by referring to Figure 1. Thus when the worm is rotated in one direction the pin 36 will be engaged by the worm and shifted longitudinally of 35 the sleeve 38 until it reaches the end groove 39 whereupon it will remain seated in said groove while the sleeve continues to rotate. The same action will take place when the sleeve is rotated in the opposite direction, 40 the pin 36 being fed back toward the other end of the sleeve 38 and there remaining in the end groove 39 during the further rotation of the sleeve.

A stop pin 40 is extended from the bell 45 crank 33 and works back and forth between opposed stop rods 41 slidably within casings 42 supported by brackets 43 extending laterally from the housing. Springs 44 are arranged within these casings and 50 thrust against the stop rods so as to press them toward the bell crank 33. The rods are limited in their movement by nuts 45 adjustably engaging them and bearing against tubular plugs 46 adjustably mounted 55 in the casings and constituting plug bearings for the springs 44. Obviously each time the bell crank 33 is shifted it will come against one of the stop rods 41 and be cushioned thereby and thrown back toward 60 the center so as to again engage the worm thread on its reversal.

A bracket 47 is extended from the cross head and the shaft 14 extends through this bracket and also through the bracket 43. 65 The sleeve 38 is mounted on that portion of

the shaft between the two brackets 43 while supported on the shaft 14 and between bracket 47 and the adjacent bracket 43 is a feed nut 48. The shaft 14 is screw threaded as shown at 49 and the nut 48 engages the threaded portion so that when the shaft is rotated said nut and the entire cross head is shifted longitudinally of the carriage and relative to the arm 16.

The cross head has a depending frame 49' 75 provided with reinforcing braces 50 and carrying at its lower end a buffer or block 51. Journalled between the braces 50 are upper and lower supplemental sheaves 52 and 53 between which the cable A extends and 80 these sheaves are adapted to be adjusted toward or from each other by means of screws 54 located in brackets 55 on the outer sides of the braces and which support the bearings 56 of the sheaves. Obviously by 85 adjusting these screws the sheaves can be moved toward or from each other, thereby to be in proper relation to the supporting cable A therebetween.

Carriers one of which has been indicated 90 by broken lines at B are adapted to be supported by the cable A.

At the beginning of the movement of the carriage under the pull of the out-haul line a series of carriers B is mounted on the 95 arm 16 between the cross head and the shoulder 24. The rotation of one of the sheaves 1 will result in the rotation of shaft 14 and, consequently, the pin 36 will be shifted longitudinally of the sleeve 38 by the worm 37, thus causing the bell crank to actuate segmental gear 32 and impart a one-half revolution to the gear 31. Thus the pin 30 will be moved through 180° from the position shown in Figure 2 and will cause 100 the push bar 27 to move from the position shown in said figure to a point where one end is extended toward the shoulder 24 a distance equal to twice the throw of the pin 30. As the carriage continues to travel 105 along the cable A and the shaft 14 continues to rotate, the nut 48 will be fed along the threaded portion of the shaft 14, causing the cross head to move along arm 16 and the bar 27 to thrust against the carrier B nearest thereto. Thus the outer end of the carrier will be pushed over the shoulder 24 and onto the cable A and after the carriage has moved a predetermined distance another carrier will be thrust over shoulder 24 and 110 gravitate to the cable A. Thus when the carriage completes its outward trip all of the carriers will have been deposited on the cable A at substantially equal distances. Counterbalancing weights 20 serve substantially to support the weight of the carrier while on the arm 16, the upper sheave 52 supporting a portion of the load of the carriers until they have been discharged after 115 which the sheave 53, by thrusting upwardly 120

against the cable A, receives the excess pressure due to the overbalancing of the arm 16 by the weights 20. By providing the sheaves 52 and 53 it will be noted that the 5 horn 23 is held substantially at a uniform distance from the cable A whether or not the carriers B are mounted on the arm 16.

When the carriage begins its return stroke the worm 37 promptly shifts bell 10 crank 33 so as to pull the push bar 27 backwardly away from the shoulder 24 adjacent which the cross head is located. Thus sufficient space is left to receive the first carrier B when the carriage starts its return 15 movement. As the carriage continues to move back toward the starting point the cross head gradually moves away from the shoulder 24, thus providing ample space to receive the additional carriers as they are 20 picked up by the horn 23 and directed onto the arm 16.

Although one form of mechanism for operating a push bar 27 has been shown and described, it is to be understood that other 25 constructions of differential mechanisms can be employed for accomplishing the same purpose. Also instead of utilizing the counterbalance weights and levers illustrated and described, other arrangements 30 can be employed for maintaining the horn 23 in proper relation to the cable A.

What is claimed is:—

1. The combination with a track cable, of a carriage movable therealong, and including a rotatable cable engaging sheave, an arm movable with and adapted to swing upwardly and downwardly relative to the carriage, yielding means for holding the free end of the arm normally elevated, a 40 cross head slidable longitudinally of the arm, means operated by the rotation of the sheave for moving the cross head toward or from the horn, a push device movable relative to the cross head, and means operated 45 by the initial movement of the cross head toward or from the horn for moving the push device in the direction of movement of the cross head but at a greater speed than the cross head.

2. The combination with a track cable, a carriage movable therealong, an arm movable with the carriage for supporting fall rope carriers and a pick-up horn at the free end of the arms, of a cross head upon the 55 arm, means operated by the movement of the carriage, horn first, for moving the cross head toward the horn and, by the movement of the carriage in the opposite direction, for moving the cross head away from the horn, a push device movably mounted on the cross head, and means operated by 60 the initial movement of the cross head to-

ward or from the horn for moving said push device toward or from the horn respectively at a greater speed than the cross head. 65

3. The combination with a track cable, of a carriage movable therealong, an arm tiltably connected to and projecting beyond one end of the carriage, a horn at the free end of the arm, yielding means connected 70 to the arm for holding the horn normally elevated to one limit of its movement, and superposed means connected to the arm for engaging the track cable to maintain the horn substantially in a predetermined relation to the cable under all conditions. 75

4. The combination with a track cable, of a carriage movable therealong, an arm tiltably connected to and projecting beyond one end of the carriage, a horn at the free end of the arm, yielding means connected to the arm for holding the horn normally elevated to one limit of its movement, a frame depending from the arm and superposed cable engaging sheaves adjustably carried 80 by the frame for maintaining the arm substantially in a predetermined relation to the cable irrespective of the load carried by the arm. 85

5. The combination with a track cable, of a carriage movable therealong and including a rotatable cable engaging sheave, a substantially counterbalanced arm movable with the carriage for supporting fall rope carriers, a pick up horn at the free end of the arm, a cross head supported by the arm, sheaves movable with the cross head and engaging the cable for limiting the up and down movement of the horn relative to the cable, and means operated by the rotation 90 of the sheave for moving the cross head toward or from the horn. 95

6. The combination with a track cable, of a carriage movable therealong and including a rotatable cable engaging sheave, an 105 arm fulcrumed on the carriage, means for substantially counterbalancing the arm, a pick up horn at the free end of the arm, a cross head movable along the arm, a push device carried by and movable relative to 110 the cross head, means operated by the rotation of the sheave for shifting the cross head relative to the arm and for moving the push device in the direction of movement of the cross head during the initial 115 portion of said movement of the cross head.

In testimony that I claim the foregoing as my own, I have hereto affixed my signature in the presence of two witnesses.
